UNITED STATES PATENT OFFICE.

FRANK M. MARCY, OF WORCESTER, MASSACHUSETTS.

SPOOL OR BOBBIN.

SPECIFICATION forming part of Letters Patent No. 350,985, dated October 19, 1886.

Application filed June 21, 1886. Serial No. 205,827. (No model.)

To all whom it may concern:

Be it known that I, FRANK M. MARCY, a citizen of the United States, residing at Worcester, in the county of Worcester and State 5 of Massachusetts, have invented certain new and useful Improvements in Spools or Bobbins; and I do hereby declare the following to be a full, clear, and exact description of my invention.

10 Heretofore spools have been made of wood, and after being in use sometime the heads are liable to become detached from the barrel of the spool, or to check or crack, and in winding the thread gets into the cracks in the heads 15 and breaks and causes more or less inconvenience.

To obviate these difficulties, I make the heads of my spools of metal and suitably fasten them to the wooden barrel of the spool.

20 In order that my invention may be fully understood, I will proceed to describe it with the aid of the accompanying drawings, in which—

Figure 1 represents a central section of a circular metallic head, A, with a circular hole, 25 A', in the center of the head A, and the outer edge of the head A turned at right angles or more or less to the surface of the head A, forming the lip A".

Fig. 2 represents a metallic tube, B, of sufficient length, with the diameter of the said tube B enough greater to allow one end to be cut down to the size of the hole A' in the center of the head A, Fig. 1, forming the shoulder E on the tube B at a distance from 35 the end of the tube B to allow the said end of the tube B to project a sufficient distance through the hole A' in the head A, Fig. 1, and the other end of the tube B is turned inward, forming the flange B". I now take 40 the tube B and drive the end having the shoulder E through the circular hole A' in the circular head A, Fig. 1, until the head A is firmly set against the shoulder E. I then turn outward the part of the tube B projecting 45 through the hole A' in the head A firmly against the surface of the head A, as shown in Fig. 3, forming the flange B' on the tube B, thus preventing the head A from drawing off.

Fig. 3 represents the metallic head A, with 50 the circular hole A' in the center of the head A, the lip A", formed on the outer edge of the head A, and the tube B driven into the hole A' in the head A up to the shoulder E on

the tube B, and the flange B' turned outward against the surface of the head A, and the 55 flange B" turned inward on the other end of the tube B.

Fig. 4 represents the barrel C of the spool, of wood, and at each end enlarged the hole x, running the entire length of the barrel C to the 60 outside diameter and to the depth of the length of the tube B, forming the hole C', so the tube B will be a tight fit when driven into the hole C'. I now make another hole, C", at the base of the hole C', of a diameter equal, or nearly 65 so, to the diameter of the space left at the end of the tube B, Fig. 2, that has the flange B", said hole C" to be of a sufficient depth.

Fig. 5 represents the plug D, made of wood, with the hole x running through it, with the 70 diameter of one part of said plug D to be of the diameter of the inside of the tube B, and the length of the plug D of this diameter to be the length of the outside of the tube B, and the diameter of the balance of the plug D to 75 be the same as the diameter of hole C", Fig. 4. After covering the outside surface of the tube B as it is left at Fig. 3 with a cement, I drive it firmly into the hole C' in the barrel C till the end of the barrel C rests firmly against the 80 head A, then cover the entire outside of the plug D with a cement and force it into the inside of the tube B till the end of the plug D is flush with the surface, or nearly so, of the head A, and by this means the flange B" of the 85 tube B is forced into the space on the plug D, where the two diameters come together, and the part of the plug D having the smaller diameter is forced into the hole C" of the barrel C, thus firmly fastening the metallic head A 90 to the wooden barrel C, as shown in Fig. 6.

Having fully described my invention, what I desire to claim and secure Letters Patent on is—

In a spool or bobbin, the combination of the 95 metallic head A, having the lip A", the metallic tube B, having the shoulder E and flanges B' and B", the wooden plug D, and the wooden barrel C, all substantially as shown and described.

FRANK M. MARCY.
